UNITED STATES PATENT OFFICE.

WILLIAM D. WALKER, OF SAN FRANCISCO, CALIFORNIA.

SKIRT-MARKER.

1,248,959.

Specification of Letters Patent.

Patented Dec. 4, 1917.

Application filed December 12, 1916. Serial No. 136,421.

To all whom it may concern:

Be it known that I, WILLIAM D. WALKER, a citizen of the United States, residing at San Francisco, in the county of San Francisco and State of California, have invented 5 certain new and useful Improvements in Skirt-Markers; and I do hereby declare the following to be a full, clear, and exact description of the invention, such as will enable others skilled in the art to which it appertains to make and use the same.

In the use of skirt markers of the type which embody substantially parallel blades adapted to receive the skirt to be marked 15 therebetween considerable inaccuracy has resulted owing to the fact that the material of the skirt often moves relatively to the blades after the latter have been pressed together and before the act of marking the 20 skirt is indulged in. It is therefore the purpose of my invention to provide a skirt marker of the type referred to embodying an improved construction which will positively eliminate movement of the material 25 relatively to the blades after the latter have been pressed together even though the pressure on the blades should be relaxed to an appreciable degree and through the medium of this improved construction I am enabled 30 to assure absolute accuracy in the marking of a skirt for the purpose of turning hem or for the application of trimming.

It is also my purpose to provide a skirt marker which will enable the operation of 35 marking the skirt to be accomplished with great rapidity and which at the same time will embody an exceedingly simple structure capable of being manufactured and sold at a relatively small cost.

With the above and other purposes in 40 view the invention consists in the details of construction and in the arrangement and combination of parts to be hereinafter more fully described and particularly pointed out 45 in the appended claims.

In describing my invention in detail reference will be had to the accompanying drawings wherein like characters of reference denote corresponding parts in the several views, and in which—

Figure 1 is a perspective view showing the manner of using my improved skirt marker;

Fig. 2, an edge view of the marker;

Fig. 3, a top view of the marker;

Fig. 4, a section on the line 4—4 of Fig. 1, and

Fig. 5, a section on the line 5—5 of Fig. 1.

Referring to the drawings my improved skirt marker is shown constructed from a single length of metal bent upon itself to form parallel blades A and B and lateral extensions 10 and 11 at the bottom of said blades respectively, said extensions being secured to a base 12 by suitable fastening devices 13. The blade A is provided with a plurality of spaced transversely directed recesses 14 which open through one longitudinal edge of said blade. A longitudinal groove 15 is formed on the inner side of the 60 blade A adjacent the edge thereof remote from the recesses 14. This groove may be formed by stamping the structural metal or in any other desired manner. The recesses 14 may be situated any desired distance 65 apart, such distance being preferably a fraction of an inch, and in this instance I have shown the recesses one-half an inch apart and I provide a suitable scale 16 on the blade A increasing upwardly to indicate the 70 distance of a given recess from the under face of the base 12. On the blade B I provide a plurality of transverse ribs 17 which correspond in number to the number of recesses 14 and are so positioned that when 75 the blades A and B are pressed together the ribs 17 will enter respective recesses 14. I also provide on the inner side of the blade 80 B a longitudinal rib 18 which is likewise adapted to enter the groove 15 when the 85 blades A and B are pressed together. By stamping the rib 18 and the groove 15 and the resultant rib produced by the latter I am enabled to greatly strengthen the blades A 90 and B and at the same time utilize the 95 interfitting relation of these parts to firmly hold the material against movement relatively to the blades when the latter are pressed together. In other words the groove 100 15 and rib 18 perform a double function.

In use the base 12 is placed upon the floor with the blades A and B extending upright with the skirt C inserted therebetween as clearly shown in Fig. 1. The blades are pressed together to clamp the skirt. The 105 ribs 17 will force the material of the skirt through the recesses 14 when such material can be marked with facility in a convenient manner at any desired recess. This operation is repeated around the skirt until the 110

desired number of markings are applied. It will be observed that the ribs 17 by forcing the material in the recesses 14 also serve to securely clamp the material against movement relatively to the blades or in other words prevents slipping of the material until all the pressure is removed from the blades.

What is claimed is:—

- 10 1. A skirt marker comprising substantially parallel blade members adapted to receive a skirt to be marked therebetween, one of said members having spaced openings therein, and ribs on the other member adapted to enter the openings respectively when the members are pressed together.
- 20 2. A skirt marker comprising substantially parallel blade members adapted to receive a skirt to be marked therebetween, one of said members having spaced recesses therein opening through one longitudinal edge of the member, and ribs on the other member adapted to enter the recesses respec-

tively when the members are pressed together.

- 25 3. A skirt marker comprising substantially parallel blade members adapted to receive a skirt to be marked therebetween, one of said members having a longitudinal groove in its inner face and a plurality of spaced transversely extending openings, a longitudinal rib on the inner face of the other member, and a plurality of transverse ribs on the inner face of the last named member, said longitudinal and transverse ribs being adapted to enter the longitudinal groove and transverse openings when the members are pressed together.

In testimony whereof I hereunto affix my signature in the presence of two witnesses. 40

WILLIAM D. WALKER.
